UNITED STATES PATENT OFFICE

138,074

DESIGN FOR A DOLL

James E. Bryan, Cleveland, Ohio, assignor to The Cleveland Shopping News Company, Cleveland Ohio, a corporation of Ohio

Application January 7, 1944, Serial No. 112,192

Term of patent 14 years

(Cl. D34—4)

To all whom it may concern:

Be it known that I, James E. Bryan, a citizen of the United States and a resident of Cleveland, county of Cuyahoga, and State of Ohio, have invented a new, original, and ornamental Design for a Doll, of which the following is a specification, reference being had to the accompanying drawing, forming a part thereof.

In the drawing:

Fig. 1 is a front elevational view of a doll showing my new design; and Fig. 2 is a side elevational view thereof.

I claim:

The ornamental design for a doll, substantially as shown.

JAMES E. BRYAN.
